UNITED STATES PATENT OFFICE.

EARL H. CUMMINGS, OF BISMARCK, NORTH DAKOTA.

DRAINING VESSEL.

1,299,135.

Specification of Letters Patent.

Patented Apr. 1, 1919.

Application filed February 13, 1918. Serial No. 217,012.

To all whom it may concern:

Be it known that I, EARL H. CUMMINGS, a citizen of the United States, residing at Bismarck, in the county of Burleigh and State 5 of North Dakota, have invented certain new and useful Improvements in Draining Vessels, of which the following is a specification, reference being had to the accompanying drawings.

10 This invention relates to certain improvements in draining vessels and has relation more particularly to a device of this general character adapted for use in connection with wash boilers, and it is an object of the invention 15 to provide a draining vessel with novel and improved means whereby it may be supported in an elevated position relative to the wash boiler in order to permit draining of the clothing or other article within the 20 vessel.

The invention consists in the details of construction and in the combination and arrangement of the several parts of my improved draining vessel wherein certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood I will now proceed to describe the same with reference to the accompanying drawings wherein:

Figure 1 is a longitudinal sectional view 40 by a wash boiler; and

Fig. 2 is a view in end elevation of my improved vessel as herein set forth.

As disclosed in the accompanying drawings B denotes a wash boiler of a conventional type and in which is adapted to be inserted the vessel or basket V containing clothing or other articles to be submerged in the water within the boiler B.

50 My improved vessel includes the upper and lower frames 1 of predetermined configuration and which are connected by the perforate wall 2 formed preferably of a wire mesh of predetermined gage. The lower frame 1 also has operatively engaged therewith a perforate bottom 2 also preferably formed of a reticulated fabric of de-

sired mesh. Disposed transversely of the lower frame 1 and substantially at its longitudinal center is the reinforcing strip 3 which is positioned below the bottom 2 and 60 serves as a further support for the bottom 2.

Each end of the upper frame 1 is provided with a pair of transversely disposed tubular members or barrels 4 having their bars horizontally directed and substantially in alignment one with the other. S denotes a supporting member preferably formed from a single length of material and which has its central portion 5 substantially straight with the extremities of said straight portions continued by the right angular extensions 6 of a predetermined length. The extensions 6 are continued by the outwardly directed right angular extensions 7 which are loosely directed through the sleeves or barrels 4 70 whereby the holding member S is pivotally engaged with the vessel V and capable of swinging or rocking movement in a direction longitudinally of the vessel or basket. The extensions 7 are continued by the downwardly directed elongated portions 8 preferably arranged in convergence and also outwardly inclined relative to the extension 6. The free extremities of the portions 8 are returned as at 9 and the upper or inner portions thereof are bent to afford the downwardly or outwardly facing hook members 10. Pivots engaged with each of the central portions 5 of the supporting member S is the handle or hand grasp 11 substantially U-shaped in form with its free extremities operatively engaged with the central portion 5.

The hand grasps or handles 11 afford convenient means whereby the vessel or basket V may be readily inserted within or removed from the boiler B and when it is desired to hold the vessel or basket V in an elevated position relative to the bottom of the boiler B in order to drain the clothing or other contents 95 of the vessel or basket V the supporting devices S are rocked in a direction away from the ends of the vessel or basket so that the downwardly or outwardly facing hook members 10 may straddle the upper marginal portion of the boiler B as illustrated in Fig. 1 of the drawings. It is also to be understood that the longitudinal diameter of the vessel or basket V relative to the corresponding diameter of the boiler B is such as to permit 100 the vessel or basket V to be rested upon the bottom of the boiler B without obstruction 110

or hindrance being offered by the hook members 10 when the supporting devices has been rocked to bring the returned portions 9 of the members S in close proximity 5 to the ends of the vessel or basket V.

In the use of my vessel or basket V water within the boiler is permitted to circulate through the clothing and therearound between the vessel or basket V and the boiler B 10 so that the water may readily bubble about and through the clothing to materially effect the action thereon.

My improved vessel or basket is also intended to be used as a home canning outfit 15 in connection with the ordinary wash boiler and can be used for canning fruits, vegetables or other matter capable of being canned or preserved. The jars or the like containing the matter to be canned is placed 20 in the vessel or basket V, and said vessel or basket is supported in an elevated position within the boiler so that the desired steaming action can be had. The basket is also maintained elevated to drain and cool to 25 any temperature desired.

From the foregoing description, it is thought to be obvious that a draining vessel constructed in accordance with an embodiment of my invention is particularly well 30 adapted for use by reason of the convenience and facility with which it may be assembled and operated and it will also be obvious that my invention is susceptible of some change

and modification without materially departing from the principles and spirit thereof 35 and for this reason I do not wish to be understood as limiting myself to the precise arrangement and formation of the several parts herein shown in carrying out my invention in practice except as hereinafter 40 claimed.

I claim:—

In combination with a draining vessel, a supporting member coacting with the opposite ends thereof, each of said supporting 45 members being formed from a single length of material having a central portion substantially straight with the extremities of said portion continued by right angular extensions, said extensions being continued by 50 outwardly directed right angular portions pivotally engaged with the vessel, said last named portions being continued by downwardly directed elongated portions inclined 55 outwardly relative to the right-angular extensions at the opposite ends of the straight portions, said last named portions being provided with downwardly facing hook members.

In testimony whereof I hereunto affix my 60 signature in the presence of two witnesses.

EARL H. CUMMINGS.

Witnesses:

T. E. McCURDY,
DOROTHY E. TILMOOT.
